UNITED STATES PATENT OFFICE

ABRAHAM NOVICK, OF FLUSHING, NEW YORK, ASSIGNOR, BY MESNE ASSIGNMENTS,
TO UNITED STATES ENVELOPE COMPANY, OF WORCESTER, MASSACHUSETTS, A
CORPORATION OF MAINE

SANITARY DRINKING CUP

Application filed March 18, 1930. Serial No. 436,678.

This invention relates to sanitary drinking cups made of paper or the like which are adapted to be used once and thrown away. Such cups are ordinarily arranged in stack 5 formation and placed in a holder in such manner that they may be removed one by one from the bottom of the stack.

It is an object of the present invention to provide a one-piece drinking cup of the kind 10 referred to having a tab at the lower end thereof which may be seized for facilitating withdrawal of each cup singly from the bottom of the stack.

It is a further object of the invention to 15 provide a one-piece drinking cup of the kind referred to having a large volumetric capacity as compared with the surface area of the material required for manufacture of the cup.

It is a further object of the invention to 20 provide a one-piece cup having a generally conical body but a polygonal base (preferably square). The body of a cup so shaped will have considerable rigidity and will not, therefore, be likely to collapse in the hand.

25 Other objects and advantages will herein-after appear.

In the drawings forming part of this specification,

Figure 1 is a view in rear elevation of a 30 finished cup embodying the present invention;

Figure 2 is a view in front elevation of a stack of cups like that disclosed in Figure 1;

Figure 3 is a plan view of the cup illustrated in Figure 1.

Figure 4 is a bottom plan view of the same cup;

Figure 5 is a view in rear elevation partly 40 broken away of a cup similar to that of Figure 1 but having a beaded rim and having the bottom tabs folded in;

Figure 6 is a fragmentary plan view of a paper web illustrating how the cup blanks 45 are cut;

Figure 7 is a view of a completely cut but unfolded blank associated with the former on which it is folded;

Figures 8, 9, 10, 11, and 12 are fragmentary 50 views illustrating the succeeding steps which

result in the completion of the cup of Figure 1.

Referring first to Figures 6 to 12, the blanks 1 are first cut in the form shown in Figure 6 from a paper web 2. Each blank has an 55 arcuate upper edge 3 and an arcuate lower edge 4. The lower edge 4 is discontinuous, the lower margin being indented by notches 5 and 6 to facilitate the subsequent formation of the cup bottom and the folding of tabs. 60 After the blanks have been cut in the form shown in Figure 6, they may be regarded as divided along the line 7 and also along the lines 8, 9, 10 and 11 to define tab flaps 12 and 13 and bottom flaps 14, 15 and 16. This is a 65 purely imaginary subdivision, however, referred to at this point for facilitating the ensuing description. The tab flap 12 may also be regarded as divided along lines 17 and 18 and the tab flap 13 may be regarded as 70 divided along lines 19 and 20. Adhesive 21 is applied to the tab flaps and to the bottom flap 15 as illustrated in Figure 7, and adhesive 22 is applied to a margin of the body and to the bottom flap 16 as illustrated in this figure. 75 The upper edges of the flaps 12, 15 and 13 are of equal length and would form chords of a circle drawn concentric with the upper circular edge 3 of the blank. The upper boundaries of the bottom flaps 14 and 16 80 would also form chords of this circle but they are not necessarily of the same lengths as the other chords referred to since in the finished cup these flaps overlap one another, the combined effective length of the upper edges 85 of the two flaps being then equal to the length of the upper edge of any one of the other flaps.

Preparatory to folding, the blank is associated with a former 23 as illustrated in 90 Figure 7. This former may be described roughly as generally frusto-conical in shape, but it is not really so because the generally conical form is modified to provide a square base. The portion of the former around 95 which the upper edge of the blank is wrapped is a circular or substantially circular cross section. The bottom of the former is considerably smaller in cross section and is square. The former has four flattened sides 100

and the shape of the former is such that its perimeter at any point is equal to the circumference taken at a corresponding height on the frustum of a cone having the circumference of the larger base thereof equal to the circumference of the rim of the finished cup illustrated in Figures 1 to 4 and having the circumference of the smaller base thereof equal to the perimeter of the square base of the cup. In other words, the blank, which is obviously adapted to be wrapped upon the frustum of such a cone, is also adapted to be wrapped snugly upon the former as illustrated and to fit it at every point. When the blank 1 has been associated with the former 23 in the manner illustrated in Figure 7, the left hand wing of the blank is folded around the former to the position shown in Figure 8. The right hand wing of the blank is then folded around the former to the position shown in Figure 9, thus bringing the adhesive 22 into engagement with the outer face of the body and with the bottom flap 14 of the blank. The flaps 14 and 16 now form jointly a rear bottom flap which is next folded in against the flat bottom of the former as illustrated in Figure 10. The front bottom flap 15 is then folded in against the bottom of the former so that the adhesive 15 lies against the outer face of the rear bottom flap. As an incident of the folding in of the front and rear flaps, the lines 8 and 9 are brought into coincidence with the left lower edge of the former and the lines 10 and 11 are brought into coincidence with the right lower edge of the former. At the same time, the tab flaps are folded along the lines 17, 18, 19 and 20, these lines defining the lower boundaries of the side tabs. The notches 5 and 6 facilitate the folding and correct forming of the tabs and obviate the overlapping of an objectionable number of thicknesses of paper on the tabs. The side tabs are illustrated in Figure 11 as extending outward horizontally, and in Figure 12 as folded up against the sides of the cup. They may, if desired, be pasted against the sides of the cup and be utilized as abutments or thrust members to be engaged by mechanical separating means for withdrawing the cups singly from the stack. This completes the manufacture of the cup so that it may now be removed from the former and placed in a stack as illustrated in Figure 2.

The cup manufactured as described has a large volumetric capacity for the amount of paper used, because the base as well as the top of the cup is of substantial cross sectional area. The blanks, moreover, are of regular shape so that little waste of material is involved in cutting them from a web.

The tabs 12 and 13 when folded up as illustrated in Figure 12 serve two functions: They space the body portion of each cup from the body portion of the next one above

it in the stack, sufficiently to prevent the lowermost cup from frictionally dragging the next cup down with it; and they also provide means whereby the cup may be moved outward without the necessity for squeezing the body portion of it. The tab is located at the very bottom of the cup and is, therefore, ideally situated for applying tractive force to the cup without likelihood of binding the cup against the cup next above it in the stack and without liability of disarranging the stack.

In Figure 5 disclosure is made of a cup similar in all respects to the cup already described with the exception that the tabs 12 and 13 are folded inward against the bottom of the cup instead of outward and upward against the sides as in Figure 1, and with the further exception that the upper margin of the cup is rolled to form a beaded rim 24.

I desire it to be understood that various departures from the specific embodiment described in detail will occur to those skilled in the art without, however, violating the spirit of my invention nor departing from the scope of the appended claims.

I claim:

1. A non-collapsible sanitary drinking cup, adapted to form one of a nested stack of cups, comprising a body portion of tapering cross section, bottom flaps folded inward and adhesively connected to form a flat base, and means forming an integral pull flap at the lower extremity of the cup, which serves to space the cup from an adjoining cup of the stack.

2. A non-collapsible sanitary drinking cup comprising a body portion of tapering cross section, bottom flaps folded inward and adhesively connected to form a flat base, and means forming a pair of integral pull flaps at opposite sides of the lower end of the cup, said pull flaps overlying the lower margins of the sides of the cup and serving to space the body portion thereof from the body portion of a similar cup in which it is inserted.

3. A non-collapsible sanitary drink cup comprising a body portion of tapering cross section, bottom flaps integral therewith, folded inward and adhesively secured together to form a flat base, and plural ply pull tabs also integral with the body portion and directly connected with the bottom flaps to assist in sealing the bottom of the cup, and to space the cup from an adjoining cup of the stack.

In testimony whereof I have affixed my signature to this specification.

ABRAHAM NOVICK.
